UNITED STATES PATENT OFFICE

156,304

DESIGN FOR AN AGING AND REFRIGERATING DISPLAY CABINET

Beverly E. Williams, Chicago, Ill.

Application December 31, 1946, Serial No. 135,883

Term of patent 14 years

(CL D80—11)

To all whom it may concern:

Be it known that I, Beverly E. Williams, a citizen of the United States, residing at Chicago, Cook County, Illinois, have invented a new, original, and ornamental Design for an Aging and Refrigerating Display Cabinet, of which the following is a specification, reference being had to the accompanying drawing, forming a part thereof.

Figure 1 is an end elevational view and Figure 2 is a plan view of the aging and refrigerating display cabinet showing my new design. The other side, not shown, is substantially the same as the side shown.

I claim:

The ornamental design for an aging and refrigerating display cabinet, as shown and described.

BEVERLY E. WILLIAMS.
